United States Patent Office

JULES FRANCOIS MATHIAS AND DÉSIRÉ MATHURIN LEGAT, OF PARIS,
FRANCE.

Letters Patent No. 65,926, dated June 18, 1867.

IMPROVEMENT IN MACHINE FOR COATING HATS.

The Schedule referred to in these Letters Patent and making part of the same.

TO ALL WHOM IT MAY CONCERN:

Be it known that we, JULES FRANCOIS MATHIAS and DÉSIRÉ MATHURIN LEGAT, of Paris, France, have invented a new and improved Machine for Manufacturing Sham Beaver Hats, and similar articles, and which we call a Pulvi-Felting Machine; and we do hereby declare that the following is a full, clear, and exact description thereof, which will enable others skilled in the art to make and use the same, reference being had to the accompanying drawings, forming part of this specification,

This invention relates to a certain machine for coating hats or hat-frames with a powder of fur, wool, or other substance. The hat or frame to be coated is laid on an elastic support, and coated, powdered, and dried on both sides without its being necessary to lay hands on its surface until finished. We take a certain number of hat-frames previously coated with some glutinous substance, place them on suitable frames, and secure them to a shaft of peculiar form passing horizontally through a closed chamber. This shaft rotates and reciprocates, and thus imparts to the frames a slow rotary motion, and at the same time a rapid rocking or reciprocating motion, so that the inner and outer surfaces of the hat-frames will be presented to the action of a strong continuous current of felting powder, in order to be, by a single operation, completely and appropriately coated. The continuous current of felting powder is produced by special fan, provided with screws, moving in the closed chamber.

The annexed drawings, and a description of all the parts constituting our machine, will make our invention better understood.

Figure 1 is a vertical longitudinal sectional view of our machine through x x , fig. 2.

Figure 2 is a cross-sectional view of the same.

Similar letters of reference indicate like parts.

A is a chamber in which are placed the hat-frames to be coated. The framing forming the sides of the chamber is fitted with panels, which will be hereinafter described, some of which are stationary and others movable at will. The two extreme ends of the framing are intended to hold the bearing and moving pieces. B is a fan for exhausting the felting powder from the lower part of the chamber A, in order to force it immediately towards the upper part, so as to form a strong endless current in the interior of said chamber. C are screws with equal threads, but inversely inclined on the fan-shaft and each side of the wings, so as to bring the felting powder from the lower part of the chamber A to the inside of the fan-drum, placed partly inside of the said chamber, and communicating therewith through the two openings formed laterally and opposite to the screws. D is the shaft of the fan or ventilator and its screws. E and E' are pulleys fixed on said shaft D for receiving and imparting motions. F is the force-conduit of the fan, and G the swan-neck establishing communication between the conduit F and the chamber A, and terminates in a long slot, r, through which comes with great rapidity the felting powder forced in by the fan. H is a horizontal and I a counter-shaft imparting, by means of pinion M on I, and L on H, rotary motion to shaft H, and consequently to the hollow shaft K, which carries the hat-holders. The shaft K surrounds the shaft H, and is held concentrically with that shaft by means of springs R, which are secured to projections S on H, and S' on K, and in such manner that the shaft K will rotate with the shaft I. N is a spur-wheel, forming part of a sleeve, p', which turns loose on the end of shaft H, being actuated by a pinion, O, on shaft J. P is a beating gear formed of two toothed coupling-boxes p and p', one of which, p', formed with the spur-wheel N, is loose on the central shaft H, and the other, p, moves only in a longitudinal direction on said shaft, so that as the part p' is revolved, p will be thrown against the end of the shaft K, and then moved back by a spring, Q, which continually brings the coupling-box p in contact with p'. T represents one of three arms affixed to the coupling-box p of the beater P, so as to communicate the shocks of the latter to the hollow shaft K in hitting the projection t formed on the end of said hollow shaft. The intensity of the shocks may be regulated by compressing more or less the spring Q, between the end of shaft K and the coupling-box p of the beater. U are screw-handles serving to fix the arms T on the coupling-box p, and to cause the central shaft to turn with the hollow one for more readily fixing thereto or withdrawing therefrom the hats, all the straps being on the loose pulleys. V and V' are pulleys fixed on the counter-shaft I for receiving and imparting motion. X and X' are pulleys fixed on the counter-shaft J for receiving and imparting motion. Y

are supports for shafts I and J. Z are flexible three-branched supports, terminating in fixed points for fixing thereto the hat-frames; and secured in loops a fixed on the hollow shaft, as shown. b is a movable panel, forming a door, hinged on its lower edge. c e' are panels, that may be taken out to facilitate access to the chamber. e is a partition-valve, oscillating around its axis o for directing the current of feltering powder through the swan-neck conduit on the hats, or into the passage f, in order to expel the powder from the chamber when the colors are to be changed, said valve being opened or closed by a rod, k. At the end of the passage f is hung a bag, which allows the air to pass through it, but retains the powder as it is driven through the passage from the chamber. The openings formed in the partitions or panels for the passage of the shafts are provided with leather washers, rubbing against the shafts so as to prevent leakage.

I will now describe the working of the machine.

The operator will fix the hat-bodies on the hollow shaft K by introducing the lower part of each support Z into the projections h, provided with set-screws for that purpose. He will shut the door b after throwing into the lower part of the chamber some handfuls of the feltering powder of the desired hue to serve for the whole or part of the day's work. He will bring the straps (moving on the loose pulleys) on the fixed pulleys, and the operation of feltering is then going on. The operator then brings down the straps on the loose pulleys in order to stop the movement of the machine. He opens the door b, undoes the screws from the projections h, and withdraws the hats, care being taken to touch but the supports of the articles, which are then conveyed to the drying-room, from whence they are taken out for use. The hats may be transferred from the machine to the drying-room by being fixed through said supports on a perforated rod, by means of which they are carried. One person is required to work the machine, and two more, either women or boys, for coating the hats which are to feed it. The change of colors is obtained by taking from out the machine the feltering powder contained therein, and substituting another therefor. To remove the powder in the machine it is necessary only to fasten a bag at the end of the passage f, and turn the valve to the position shown in red in fig. 1; then set the fan in operation, and the powder will be blown through the passage and into the bag. It is only when the fan has nothing more to expel that all things are set again in their original state, and that the feltered powder of the desired color is fed into the chamber.

By this new process hats will be obtained of a notable finish, as the feltering powder, projected in a regular manner on their surface by a strong continuous current of air, will impart to them a brightness and suppleness which will, in our opinion, match the true and most genuine beavers.

Having thus described our invention what we claim as new, and desire to secure by Letters Patent, is—

1. A machine for feltering hats, made and operating substantially as herein shown and described.
2. The hollow shaft K, combined and connecting with the shaft H by means of springs R R, substantially as herein shown and described.
3. The beating apparatus P, in combination with the spring Q, substantially as herein shown and described.
4. The arrangement of the valve e and passage or conduit f, in combination with the channel F and face B, all made and operating substantially as herein shown and described.

MATHIAS,
LEGAT.
